CLAIM

The ornamental design for a valve-actuating handle assembly, as shown.

DESCRIPTION

FIG. 1 is a perspective view of the valve-actuating handle assembly according to the invention;

FIG. 2 is an elevational side view of the handle assembly, both sides being identical;

FIGS. 3 and 4 are end views taken from the left and right sides, respectively, of the handle assembly of FIG. 2; and, FIG. 5 is a top view of the handle assembly.
